UNITED STATES PATENT OFFICE.

MAX FELLMAN, OF COLUMBUS, OHIO.

DESIGN FOR A BADGE.

51,689.

Specification for Design.

Patented Jan. 15, 1918.

Application filed November 19, 1917. Serial No. 202,876. Term of patent 3½ years.

To all whom it may concern:

Be it known that I, MAX FELLMAN, a subject of Russia, residing at Columbus, in the county of Franklin and State of Ohio, have invented a new, original, and ornamental Design for Badges, of which the following is a specification, reference being had to the accompanying drawing, forming part thereof.

The figure is a plan view of a badge, showing my new design.

I claim:

The ornamental design for a badge, as shown.

MAX FELLMAN.
